UNITED STATES PATENT OFFICE

158,826

CAT OR SIMILAR ARTICLE

Charles J. Wintergreen, Chicago, and Lloyd C.
Oliver, Villa Park, Ill.

Application December 1, 1948, Serial No. 149,904

Term of patent 7 years

(Cl. D34—5)

To all whom it may concern:

Be it known that we, Charles J. Wintergreen and Lloyd C. Oliver, both citizens of the United States and residents of Chicago, in the county of Cook and State of Illinois, and Villa Park, in the county of Du Page, State of Illinois, respectively, have invented a new, original, and ornamental Design for a Cat or Similar Article, of which the following is a specification, reference being had to the accompanying drawing, forming a part thereof.

Fig. 1 is a side elevational view of a cat showing our new design; and

Fig. 2 is an end elevational view thereof.

We claim:

The ornamental design for a cat or similar article, as shown.

CHARLES J. WINTERGREEN.
LLOYD C. OLIVER.
